G. P. E. STOLLE

SUBMERSION CONTROL FOR DIVERS' ARMOR

Filed Jan. 4, 1916

Inventor
George Paul Eugen Stolle
By his Attorney

Knight Bog

UNITED STATES PATENT OFFICE.

GEORG PAUL EUGEN STOLLE, OF KIEL, GERMANY.

SUBMERSION CONTROL FOR DIVERS' ARMOR.

Application filed January 4, 1916. Serial No. 70,219.

(GRANTED UNDER THE PROVISIONS OF THE ACT OF MARCH 3, 1921, 41 STAT. L., 1313.)

To all whom it may concern:

Be it known that I, GEORG PAUL EUGEN STOLLE, a subject of the German Emperor, and residing at Kiel, county of Schleswig-Holstein, State of Prussia, Germany, have invented certain new and useful Improvements in Submersion Control for Divers' Armor (for which I have filed applications in Germany December 19, 1913, 302,763; France May 20, 1914, 472,259; Austria May 18, 1914, 75,161; Hungary May 18, 1914, 67,754; England May 20, 1914, 12,419; Belgium May 20, 1914, 218,771; Russia May 8/21, 1914; Italy May 22, 1914, 63,434; Sweden May 23, 1914, 43,467; Japan July 15, 1914), of which the following is a specification.

The invention relates to armored diving dresses of the type which will completely cover the diver and is provided with a vessel which can be filled with gas and water and the gas or water contents of which can be altered at will, for the purpose of enabling the diver to control the descent and ascent.

In known arrangements of this kind the controlling vessel is provided either on the body or between the thigh parts and on the back of the armor. These arrangements are very disadvantageous inasmuch as during the ascent a tipping moment may be produced by which the diver may be put out of his natural position and thus is prevented from working.

The invention has special reference to the construction and arrangement of the controlling vessel with the object of avoiding the mentioned disadvantage and enabling the diver to maintain an upright position while descending or ascending.

In order to obtain this object I provide a controlling vessel concentric with the longitudinal axis of the armor above its centre of gravity, preferably on the head-part. Advantageously, the vessel is annular in shape and laid around the head-part. When the vessel is filled with water, this arrangement, owing to the displacement of the centre of gravity of the armor body, also enables the diver to assume easily an inclined or prostrate position. A further advantage of my arrangement consists in that a compact design is obtained. Accordingly, when the diver is working, for example at sunken

vessels, he is able to penetrate into rooms of relatively small dimensions. 55

The accompanying drawing illustrates an embodiment of the invention.

In the shown constructional form a tubular vessel 1 annular in shape and formed of metal is laid around the head-part 2 of the armor 3 and rigidly fixed to it. The vessel 1 is connected to the valve 4 of a compressed gas bottle 5 by means of a pipe 6 which extends within the vessel 1 to its top. The bottle 5 is laterally mounted on the head-part 2. 60
In the pipe 6 there is provided a valve 7 which can be operated from the interior of the armor by means of a hand-wheel 8. Another valve 9 which can be operated in a similar manner as the valve 7 is connected to the top of the vessel 1 by means of a pipe 10, and serves to regulate the escape of gas from the vessel 1. Further, a pipe 11 is provided on the bottom of the vessel 1, which allows water to pass into and out of the 65
vessel. 70

The operation of the device is as follows:

When the diver desires to sink he will open the valve 9 and the vessel 1 will be filled with water through the pipe 11 so that 80
the greatest descending power is obtained. If the diver desires to rise he will close the valve 9 and open the valves 4 and 7. The compressed gas flowing from the bottle 5 into the vessel 1 will force the water out of 85
said vessel so that the descent will be changed into an ascent.

By consequent control of the valves it is possible for the diver to adjust himself to any desired depth by controlling the contents of the vessel 1 correspondingly to the wished for depth of submersion. The distribution of weight is made so that the diver, even when the vessel 1 is filled with water, can always maintain his stable equilibrium and nevertheless assume without great exertion an inclined or prostrate position. 90

I claim:

1. An armored diving dress comprising in combination an armor, a storage vessel for compressed gas, a vessel of variable contents arranged substantially concentric with the longitudinal axis of the armor above its centre of gravity, connecting means between 100
said storage vessel and said vessel of variable 105

contents, means whereby water can enter into the last named vessel and means for controlling the gas and water contents of said last named vessel.

- 5 2. An armored diving dress comprising in combination an armor, a storage vessel for compressed gas mounted on said armor, a second vessel adapted to contain gas, mounted on said armor substantially concentric with its longitudinal axis around its head-part, connecting means between said vessels, means for controlling the flow of gas between said vessels, communicating means between the last named vessel and the outside, and means for controlling the gas and water contents of said last named vessel.
- 10 3. An armored diving dress comprising in combination an armor, a storage vessel for

compressed gas mounted on said armor, a tubular vessel substantially annular in shape 20 and adapted to contain gas, mounted on the armor substantially concentric with its longitudinal axis around its head-part, connecting means between said vessels, means for controlling the flow of gas between said vessels, communicating means between the last named vessel and the outside, and means for controlling the gas and water contents of said last named vessel.

In testimony whereof I affix my signature 30 in presence of two witnesses.

GEORG PAUL EUGEN STOLLE.
